Primary Examiner — Austin Murphy(74) *Attorney, Agent, or Firm* — Goldberg Cohen LLP(57) **CLAIM**

I claim the ornamental design for a dish and utensil drying rack, as shown and described.

DESCRIPTION

FIG. 1 is an isometric top, right side view of a dish and utensil drying rack;

FIG. 2 is a top view thereof;

FIG. 3 is a bottom view thereof;

FIG. 4 is a front view thereof;

FIG. 5 is a right side view thereof;

FIG. 6 is a rear view thereof;

FIG. 7 is a left side view thereof;

FIG. 8 is an enlarged view of section A of FIG. 7;

FIG. 9 is a sectioned elevation left side view thereof, the section being taken in a direction of section line 9-9 of FIG. 2;

FIG. 10 is a sectioned elevation left side view thereof, the section being taken in a direction of section line 10-10 of FIG. 2; and,

FIG. 11 is a sectioned elevation left side view thereof, the section being taken in a direction of section line 11-11 of FIG. 2.

The evenly spaced broken lines in the drawings depict portions of the embodiments of the dish and utensil drying rack form no part of the claim.
